(57) **CLAIM**

The ornamental design for a foam pump dispenser, as shown and described.

DESCRIPTION

FIG. 1 is a left front perspective view of a foam pump dispenser in accordance with my new design;

FIG. 2 is an exploded view thereof;

FIG. 3 is a front elevation view of the design shown in FIG. 1;

FIG. 4 is a rear elevation thereof;

FIG. 5 is a left side elevation view thereof, a right side elevation view being a mirror image thereof; and,

FIG. 6 is a top plan view thereof.

The broken lines show portions of the design that form no part of the claimed design.

The bottom elevation view of the foam pump dispenser is not shown in the drawings or described in the specification and, therefore, forms no part of the claimed design.
